[57] CLAIM

The ornamental design for a free-standing rack for supporting and displaying a baseball, a baseball glove, baseball caps and the like, as shown and described.

DESCRIPTION

FIG. 1 is a top, front, and right side perspective view of a free-standing rack for supporting and displaying a baseball, a baseball glove, baseball caps and the like showing my new design;

FIG. 2 is a top plan view thereof; and,

FIG. 3 is a front elevational view thereof, with hidden lines depicting a baseball, a baseball glove and a baseball cap supported on and displayed by the rack, it being understood that the items depicted in hidden lines are for illustration only and form no part of the design.
